UNITED STATES PATENT OFFICE.

CHARLES B. HARN, OF SOUTH BROWNSVILLE, PENNSYLVANIA, ASSIGNOR OF ONE-
THIRD TO ARTHUR D. PRINGLE AND ONE-THIRD TO HERMAN W. TWEED, BOTH OF
BROWNSVILLE, PENNSYLVANIA.

SWITCH-LOCK.

1,092,259.

Specification of Letters Patent.

Patented Apr. 7, 1914.

Application filed December 2, 1913. Serial No. 804,300.

To all whom it may concern:

Be it known that I, CHARLES B. HARN, citizen of the United States, residing at South Brownsville, in the county of Fayette and State of Pennsylvania, have invented 5 certain new and useful Improvements in Switch-Locks, of which the following is a specification, reference being had therein to the accompanying drawing.

10 This invention relates to switch locks and has for its object the production of a simple and efficient lock for holding the switch in a set position after once having been thrown.

15 Another object of this invention is the production of a simple and efficient means for swinging the locking bar to an operative position.

20 A still further object of this invention is the production of a simple and efficient means which will prevent the removal of the key from the operating lever or switch throwing lever while the same is in an unlocked position.

25 With the above and other objects in view this invention consists of certain novel combinations, constructions, and arrangements of parts as will be hereinafter fully described and claimed.

30 In the accompanying drawings:—Figure 1 is a side elevation of the locking lever or switch throwing lever showing the same in an unlocked position and applied to the switch throwing mechanism. Fig. 2 is a top 35 plan view of the structure shown in Fig. 1, a portion of the switch throwing lever being shown in longitudinal section to illustrate the locking mechanism. Fig. 3 is an enlarged longitudinal sectional view through

40 the lock carried by the switch throwing lever. Fig. 4 is a detail perspective partly in section of the casing which carries the locking mechanism for the switch throwing lever. Fig. 5 is a sectional view taken on line 45 5—5, of Fig. 2. Fig. 6 is a detail perspective of the locking bar removed from the lock casing. Fig. 7 is a detail perspective of one of the keepers within which the switch throwing lever is adapted to fit. Fig.

50 8 is a side elevation of a portion of the lock case showing the closure plate adapted to normally close the key opening. Fig. 9 is a

detail perspective of one end of the lock casing showing a modified form of the means for shifting the tumbler bars to operate the locking bars. Fig. 10 is a detail perspective of the plate carried within the lock casing adapted to constitute a guide for the key used for throwing the locking bolt to an unlocked position. Fig. 11 is a longitudinal section through the plate and sleeve illustrated in Fig. 10.

By referring to the drawings it will be seen that the switch throwing mechanism 1 is mounted upon a supporting plate 2 having its ends fitting upon the upper face of a plurality of railroad ties which support the rails of a track. The plate 2 is provided with a downwardly bent portion 3 which supports the switch throwing mechanism, 70 and a shaft 4 is carried by the switch throwing mechanism upon which is keyed the switch throwing lever 5.

A keeper 6 is placed to either side of the switch throwing lever 5 as illustrated in Fig. 1, and each keeper comprises a base portion 7 having parallel vertically extending plates which are formed integral with the base and are held in spaced relation to constitute a pocket for receiving the switch throwing lever 5 as is illustrated in Fig. 2. The inner faces of each of the plates of the keeper 6 are provided with notches 8, which notches are adapted to receive the respective ends of the locking bar 12 carried by the switch throwing lever 5. It will be seen that these keepers 6 will constitute an efficient means for holding the switch throwing lever 5 in a set position after the same has once been swung.

The switch throwing lever 5 is provided with an elongated aperture 9 and within this aperture 9 is placed a lock casing 10 which lock casing is provided with a flange portion 11 upon one side thereof for constituting an efficient means for facilitating the securing of the lock casing 10 within the aperture 9. This lock casing 10 comprises a hollow body and within this hollow body is pivotally mounted a locking bar 12. This locking bar 12 is provided with a transversely extending shaft 13, which shaft 13 is journaled in the sides of the casing 10. This locking bar 12 is provided with squared

end portions 14 which will fit in the notches 8 formed in the keeper 6, and thereby prevent the swinging of the switch operating lever 5 until the switch operating lever is unlocked from the keeper 6 as previously described.

The lock casing 10 is provided upon its inner and outer sides with enlarged apertures 14 through which apertures 14 are 10 adapted to extend the respective ends of the locking bar 12. A tumbler rod 15 is secured to the locking bar 12 near one end thereof, as is illustrated in Figs. 2, 3 and 4, and the opposite end of this tumbler bar 15 is connected to a cleat 16, which cleat 16 is fixedly secured to one of the side walls of the casing 10. The cleat 16 is provided at its opposite end to the point where the tumbler bar 15 is secured with a notch 17 through which the 20 sliding tumbler rod 18 passes. The sliding tumbler rod 18 is connected to the tumbler rod 15 by means of a transversely extending link 19, and this slidably tumbler rod 18 is provided with a substantially U-shape key 25 receiving member 20 for the purpose of facilitating the sliding of the tumbler rod 18 within the casing 10 when a key is brought into engagement therewith and is turned. A stop shoulder 21 is formed within the casing 10 and is adapted to engage the forward end of the sliding tumbler bar 18 and limit the sliding movement thereof.

From the foregoing description it will be seen that as the sliding tumbler rod or bar 18 is moved longitudinally within the casing 10, the link 19 will be drawn toward the cleat 16, thereby raising the outer end of the tumbler rod 15, which will pull the same to the position shown in dotted lines in Fig. 3 40 and in full lines in Fig. 4 and cause the locking bar 12 to be swung to the position shown in full lines in Fig. 4 and in dotted lines in Fig. 3. When, however, the sliding tumbler bar or rod 18 is moved toward the locking 45 bar 12, the tumbler rod or bar 15 will be drawn to the position shown in full lines in Fig. 3, and in this manner draw the respective ends of the locking bar 12 within the casing 10 as clearly illustrated in Fig. 3.

50 One side of the casing 10 is provided with a key receiving aperture or key-hole 22 for the purpose of admitting a key thereto, and it should be understood that any form or design of key may be used for the purpose of employing a different key for different switches. A sliding plate 23 is mounted upon the outer face of the casing 10 and is adapted to normally close the key-hole 22 to prevent the entrance of moisture into the lock and deteriorate the interior of the lock. The plate 23 is provided with a plurality of longitudinally extending apertures 24 which work upon the rivets or pins 25. A bead portion 26 is formed upon the plate 23, and 60 this bead portion presents a means for al-

lowing the plate 23 to be gripped in order that the same may be moved longitudinally upon the casing 10.

A sleeve 30 is provided with a split lower face 31 to allow the flange or web of the key to pass longitudinally of the sleeve. A rib or bar 32 is formed upon the rear face of the plate 27 for the purpose of preventing the entire rotation of the key. It should be understood that the key is first inserted by sliding the same through the sleeve 30 and then rotating the same slightly until the web of the key comes in engagement with the notch 28. The web of the key will then engage the substantially U-shape key receiving portion of the tumbler rod 18 and the rod may in this manner be moved longitudinally by the rotation of the key. After the key has been rotated, however, it will be impossible to withdraw the key from the casing 10 until the tumbler bar or rod 18 has been returned to its normal position.

As is illustrated in Fig. 9 there is shown an embodiment of the present invention of the means for operating the sliding tumbler bar 18. The sliding tumbler bar 18 is provided with the usual key receiving pocket 20, and this pocket is adapted to receive a projecting finger 33 carried by the rotating drum 34. This drum 34 is placed within the casing 35, which casing is supported by means of an integral web portion 36 within the lock casing 10' as clearly illustrated in Fig. 9. A key receiving aperture 37 is formed in the drum 34 and of course this aperture may be formed of any desired design without departing from the spirit of the invention to receive any form of key which is desired. It should be understood, of course, that by rotating the drum 34 the sliding tumbler rod or bar 18 may be operated in the same manner as described and illustrated relative to Figs. 3 and 4.

From the foregoing description it will be seen that a very simple and efficient device has been produced for the purpose of locking a switch throwing lever in a set position and holding the same in such a locked position until some authorized person holding a key of the proper design may unlock the same.

Having thus described the invention what is claimed as new, is:—

1. A device of the class described comprising a keeper, a lever, a lock casing carried thereby, a pivotally mounted locking member adapted to be swung transversely of said lever, said keeper provided with means for receiving the respective ends of said locking lever for holding said switch throwing lever in a locked position, and means for operating said locking bar.

2. A device of the class described comprising a keeper, a switch throwing lever provided with a lock casing, a locking bar car-

ried by said casing, said casing provided with apertures formed in the sides thereof, means for throwing said locking bar through said apertures, said keeper provided with 5 means for receiving the respective ends of said locking bar and holding said switch throwing lever in a locked position.

3. A device of the class described comprising a keeper, a switch throwing lever, a 10 locking casing carried thereby, a locking bar carried within said casing and adapted to be moved within said casing for throwing the ends thereof out of said casing, a tumbler bar connected to said locking bar, a 15 sliding tumbler bar, a link connecting said first mentioned tumbler bar and said sliding tumbler bar for swinging said locking bar as said tumbler bars are operated, and means for facilitating the shifting of said sliding 20 tumbler bar.

4. A device of the class described comprising a keeper, a switch throwing bar, a lock casing carried thereby, a locking bar carried by said casing, said locking bar being pivotally mounted within said casing, a pivoted 25 tumbler bar secured to said casing, a cleat provided with a notched end, a sliding tumbler bar working through said notched end, a link connecting said sliding tumbler bar 30 with said pivoted tumbler bar, a stop for limiting the sliding movement of said sliding tumbler bar, a key receiving pocket carried by said sliding tumbler bar for facilitating the moving of said sliding tumbler 35 bar within said casing, said pivoted tumbler bar connected to said locking bar for throwing the same to an operative position, and said keeper provided with means for receiv-

ing said locking bar whereby said switch throwing bar will be held in a locked position. 40

5. A device of the class described comprising a switch throwing mechanism, an operating lever coöperating with said switch throwing mechanism, a plurality of keepers, 45 a pivoted locking bar carried by said switch operating lever and adapted to engage said keepers for holding said switch operating lever in a set position, and means for swinging said locking bar within said lever. 50

6. A device of the class described comprising a switch operating lever, a lock casing positioned within said lever, a locking bar pivotally mounted within said casing, a tumbler bar connected to said lever, a sliding 55 tumbler bar, a link connecting said first mentioned tumbler bar with said sliding bar, means for limiting the movement of said tumbler bars, a key receiving socket formed upon said sliding tumbler bar, a key guiding 60 sleeve carried within said casing and provided with a notched portion for admitting a key into engagement with said key receiving socket, means formed upon said plate for preventing the entire rotation of a key 65 after the same has been inserted therein, said casing provided with a key receiving opening, and a sliding protector plate fitting over said opening for preventing the entrance of moisture into said casing. 70

In testimony whereof I hereunto affix my signature in presence of two witnesses.
